UNITED STATES PATENT OFFICE.

PETROS G. MAVRAKIS, OF CLEVELAND, OHIO.

PORTABLE COMMODE.

1,254,255.

Specification of Letters Patent. Patented Jan. 22, 1918.

Application filed July 24, 1917. Serial No. 182,509.

To all whom it may concern:

Be it known that I, PETROS G. MAVRAKIS, a subject of the King of Greece, residing at Cleveland, in the county of Cuyahoga and State of Ohio, have invented certain new and useful Improvements in Portable Commodes, of which the following is a specification.

My invention relates to improvements in portable commodes, and it consists in the constructions, combinations and arrangements herein described and claimed.

An object of my invention is to provide a portable commode, having as one of the principal features, a pedal-operated lid so arranged with relation to a pull-bar, that the lid is braced when open forming a rest for the back of the user.

Another object of the invention is to provide a portable commode including foot-operated link and pull-bar devices which are adapted to raise a lid upon being depressed by the foot of the user, a spring being embodied to return the parts to a normal position when foot pressure is released, thus automatically tightly closing the lid.

Another object of the invention is to provide a lid strap curved to avoid the lid hinge and at the same time form an abutment for resting against an extension of a pull-bar above the pivotal point of the lid strap to the pull-bar, to form a brace for the lid when it is open.

Other objects and advantages will appear in the following specification, reference being had to the accompanying drawing in which:

Figure 1 is a central vertical section of the portable commode showing the lid closed,

Fig. 2 is a side elevation of the portable commode showing how the operating link devices are concealed from view, and

Fig. 3 is a detail sectional view showing how the curved portion of the lid strap rests against the extension of the pull-bar to brace the lid when open.

In carrying out my invention I provide the receptacle 1 which is suitably shaped to present an attractive appearance. The receptacle 1 has a bottom 2 arranged at the required distance from the top or seat 3. It will be observed that the seat 3 is suitably rounded, while the front portion of the receptacle curves outwardly from a place adjacent to the bottom 2.

A handle 4 is hinged on the receptacle 1 so that the commode may be carried from place to place. The lower end of the receptacle 1 is slotted at front and back as at 5 and 6 respectively. The slot 5 accommodates the bar 7 of a treadle 8, and it will be observed in Fig. 2 that the treadle 8 is the only visible part of the lid operating mechanism, the lid operating mechanism 65 being concealed in the bottom of the commode.

The treadle 8 is pivoted to a lever 9 which is S-shaped and is fulcrumed in the middle to a bracket 10 fixed on the bottom 2 as 70 clearly shown in Fig. 1. The bar 7 of the treadle 8 is fulcrumed on a bracket 11 also fixed on the bottom 2. The rear end of the S-shaped lever 9 is pivoted to a short arm 12 of a pull-bar 13. The short arm 12 75 moves in the slot 6 at the rear of the receptacle 1.

A spring 14 connected at its ends respectively to the bottom 2 and the S-shaped lever 9, pulls the rear part of the lever 9 up 80 thus keeping the treadle 8 in an elevated position, and also keeping the lid of the receptacle tightly closed.

The lid 15 of the receptacle is hinged at 16 to the receptacle. The rim of the lid is 85 properly shaped to conform to the shape of the seat 3 thereby snugly fitting the seat and maintaining a tight closure of the receptacle.

The pull-bar 13 has an extension 17 above the pivotal point 18 of a lid strap 19. This 90 construction is clearly shown in Fig. 3, wherein it will be seen the lid strap 19 is curved at its free end at 20. The extreme end of the lid strap 19 adjacent to the curved free end 20, is curled at 21 to form a hinge 95 at the point 18.

It will readily be understood from Fig. 3 that one of the two-fold functions of the curved end 20, is to avoid the hinge 16 of the lid, and the other is, to act as an abutment 100 for the lid against the extension 17 of the pull-bar 13 thus bracing the lid when it is open and form a back rest.

A shield 22 covers the pull-bar 13 so as to conceal it from view, the shield being either 105 made integral with the receptacle 1 or being secured thereto in any desired manner. The shield 22 is preferably open at the bottom as is also the bottom of the receptacle, thus access to the working parts may readily be 110 had, for oiling and repairing the mechanism.

The operation of the device is as follows.

The treadle 8 normally assumes the elevated position shown in Fig. 1. The treadle 8 is shown at an inclination with respect to the receptacle 1, but obviously it may be arranged in other relationships. The treadle 8 is depressed by the foot of the user, when the S-shaped lever 9 will rock on its fulcrum pulling the pull-bar 13 down.

The short arm 12 of the pull-bar moves in the slot 6 while the bar of the treadle 8 moves in the slot 5. When the treadle 8 is completely depressed, the curved end 20 of the lid strap 19 on the lid 15 will rest against the extension 17 of the pull-bar 13 as shown in Fig. 3. The extension 17 thus provides an abutment for the curved end 20 of the lid and thus braces the lid.

While the construction and arrangement of the device is that of a generally preferred form, obviously modifications may be made without departing from the spirit of the invention or the scope of the claims.

I claim:

1. In a portable commode, the combination of the receptacle having a lid hinged thereon, a pull-bar for operating the lid, said pull-bar having an extension, and a lid strap secured to the lid and fulcrumed to the pull-bar at the base of the extension, the lid strap being shaped to avoid the hinge and engage the extension when the lid is open and brace the lid.

2. A portable commode comprising a re-

ceptacle having a shield at the back and including a bottom, the receptacle formed with a housing beneath the bottom, a treadle fulcrumed in the housing and protruding at the front, a lever fulcrumed in the housing and pivoted to the treadle, means connected to the lever for holding the treadle in its normal position, a pull-bar movable in the shield and having a short arm connected to the lever, a lid hinged on the receptacle, a lid strap on the lid pivoted to the pull-bar, said pull-bar having an extension above the pivot forming an abutment for the lid strap and a brace for the lid, and a handle for the receptacle.

3. In a device of the class described, the combination of a receptacle and cover pivotally mounted thereon, a lid strap secured to said cover and projecting therebeyond, a pull bar having an extension, said lid strap being pivotally connected to said pull bar at a point below and at one side of said extension, and means for drawing said pull bar downwardly thereby swinging said cover upwardly whereby said strap will engage said extension for limiting the movement of said cover in one direction.

In testimony whereof I affix my signature in presence of two witnesses.

PETROS G. MAVRAKIS.
